JOHN H. GOSS, OF WATERBURY, CONNECTICUT, ASSIGNOR TO SCOVILL MANUFACTURING COMPANY, OF WATERBURY, CONNECTICUT, A CORPORATION OF CONNECTICUT

TUBE AND TUBE SHEET AND FERRULE THEREFOR

Application filed August 7, 1930. Serial No. 473,711.

This invention relates to tubes and tube sheets, and ferrules therefor.

It has been common practice in manufacturing water tube condensers and the like to anchor the tubes in the tube sheets by ferrules which are threaded into tapped holes in the tube sheets and bear against packing material, compressing the same. These ferrules project a substantial distance beyond the face of the tube sheets and their outer ends have screw-driver slots for manipulation by a suitable tool. This construction has the disadvantage that the ferrules form what are known as "gas pockets" adjacent the exposed ends of the tubes and the projecting ends in the path of the incoming water cause turbulence. As a result of such gas pockets and water turbulence, air is released from the flowing water and this air, or the dissolved oxygen therein, attacks the tubes. It has been found that with the construction referred to the tubes soon require replacement.

A further disadvantage of the ferrules referred to is the metal cost.

It is an object of the present invention to provide a ferrule for anchoring tubes in tube sheets such that the above mentioned disadvantages are avoided.

With this general object in view, the invention consists in the features, combinations, details of construction and arrangements of parts which will first be described in connection with the accompanying drawing and then more specifically pointed out.

In the drawing:

Figure 1 is a sectional view, with parts broken away, of a tube, tube sheet and ferrule, constructed in accordance with the invention;

Figure 2 is an end view (enlarged) of the ferrule removed; and

Figure 3 is a sectional view taken on the line 3-3 of Fig. 2.

Referring to the drawing, 4 represents a tube sheet, e. g. the tube sheet at the inlet end of a water tube condenser. Anchored in the tube sheet is a tube 5.

The tube sheet hole is reamed and tapped

in the usual way to receive a ferrule and a packing.

While the packing may be of any suitable construction, that here shown as an example comprises two rings 6, 7, of soft metal, between which is a fibre ring 8.

Threaded into the tapped hole of the tube sheet is a ferrule 9, its exterior surface having a thread 10 to this end. The inner end of the ferrule engages the packing to compress the same.

Provision is made for protecting or covering the end of the tube 5 from the inflowing water. To this end, as here shown as an example, the ferrule wall is cut away at its inner end to form an internal shoulder 11 for receiving the end of the tube 5. As shown, the radial depth of this shoulder is substantially equal to the thickness of the tube wall. With the construction described the shoulder covers the end of the tube, and ferrule wall and tube wall present a flush surface to the incoming water.

Provision is made for minimizing water turbulence. This may be accomplished by a ferrule flush with the outer face of the tube sheet and further by giving the ferrule a bell-mouth. In the embodiment here illustrated as an example, the interior wall of the ferrule flares outwardly in the form of a so-called "hydraulic curve" 12. Moreover, the outer rim of the ferrule is substantially flush with the outer face of the tube sheet. To this end, the parts are so arranged that as the ferrule is threaded into place this flush arrangement occurs when the packing is properly compressed. Thus the packing serves as a stop for positioning the ferrule.

With the construction described, the assembled structure presents a flush surface to the incoming water and this, in connection with the curve of the ferrule bore, reduces water turbulence to a minimum.

There is provided means whereby the ferrule may be manipulated by a tool and in constructions embodying the invention to the best advantage, this is accomplished in such a way that the thread of the tube sheet hole is not exposed to the incoming water. This may be accomplished by forming the flared wall 130

of the ferrule with one or more slots or notches 13, four being illustrated in the present embodiment. These notches extend from a point close to the outer rim of the ferrule to 5 a point near shoulder 11. The bottom of the notches are concaved, as appears in Fig. 3, the curve being substantially the reverse of the curve of the ferrule wall. The ferrule may be manipulated by a suitable wrench- 10 like tool having lugs shaped to enter notches 13. These notches, even though the ferrule is flush with the tube sheet, do not expose any part of the thread of the tube sheet hole to the action of the water. Moreover, they do 15 not tend to cause any water turbulence in themselves as their bottom faces are on the so-called "hydraulic curve".

At the other end of the tube 5, the ferrule may be of like construction or the old common type of ferrule may be used, since at the 20 outlet end water turbulence and gas pockets are not involved.

The ferrule described, in addition to the advantages above mentioned, is smaller in metal 25 content than the old ferrules, whereby metal cost is materially reduced.

What is claimed is:

A preformed metal ferrule for anchoring 30 a tube in a tube sheet, said ferrule having a threaded cylindrical outer wall and a bell-mouth inner front wall with a substantially cylindrical tube-engaging rearward wall and having at least one notch for receiving a manipulating tool, said notch being formed 35 in the bell-mouth inner front wall and having a concave bottom, with said notch extending from a point close to the rim of the bell-mouth to a point close to said tube-engaging rearward wall, whereby absence of angular 40 projections in said notch tends to prevent turbulence of flow.

In testimony whereof, I have hereunto set my hand.

JOHN H. GOSS.
